DESIGN FOR A MILK BOTTLE

John B. Neal, Allston, Mass., assignor of thirty-seven and one-half per cent to Frederick H. McAdams, Revere, Mass., and twenty-five per cent to Everett E. Kent, Newton, Mass.

Application February 13, 1940, Serial No. 90,234

Term of patent 14 years

To all whom it may concern:

Be it known that I, John B. Neal, a citizen of Canada, residing at Allston, in the county of Suffolk and State of Massachusetts, have invented a new, original, and ornamental Design for a Milk Bottle, of which the following is a specification, reference being had to the accompanying drawing, forming part thereof.

The drawing is a side elevation of a milk bottle embodying my new design.

I claim:

The ornamental design for a milk bottle, as shown.

JOHN B. NEAL.
